1 Claim

ABSTRACT OF THE DISCLOSURE

Improved apparatus for producing layered multi-component filaments comprising spinneret means, mixing means immediately upstream of said spinneret means, feed means for introducing spinning masses through filtration means into said mixing means, said mixing means dividing and increasing the component layers prior to terminating into the extrusion orifices of said spinneret means.

This invention relates to the production of multifilament yarns comprised of filaments having a layered, multicomponent structure. In one aspect, this invention relates to an apparatus for producing such yarns in which a mixing device having stationary elements of the type that divide and increase the number of layers in a multi-layered stream is placed upstream of a spinneret. Apparatus of this general type is described in the copending application of Arie Bezemer et al., Ser. No. 580,817 filed on Sept. 20, 1966 and now abandoned.

Heretofore, it has been recognized that multifilament yarns made up of filaments having a layered, multicomponent structure are suitable for various applications. One of the applications for such fibrillary products is in obtaining ultrafine fibers, which are difficult to make by direct spinning. To this end, one of the layered components is entirely or partly dissolved from fibrillary products. As a result, the product disintegrates into numerous fine fibers. In a different application, the yarn is processed into sheets which serve as a starting material for the manufacture of artificial leather.

An entirely different application involves the use of such products as tire yarns. As is known, tire yarns are used for the manufacture of carcass fabric for automobile tires, driving belts, and the like. The advantages of using such fibrillary products for this purpose is that the resulting yarn combines the favorable properties of the two components and shows little or none of the unfavorable properties thereof.

Another application of these multifilament yarns may consist in their use as textile yarns. By inter-mixing the two components within each filament, it is possible to realize all sorts of novel effects such as colors, crimp, and the like.

In the previously known apparatus noted above, a mixing device is positioned completely separate from the spinneret. With this arrangement, the spinning mass or masses are collectively inter-mixed before they have reached the spinning orifices in the spinneret.

It has been found that the known apparatus for producing such multifilament yarns has various drawbacks. One considerable drawback is that after the inter-mixed spinning masses have left the mixing device, they still have a long residence time in the spinning apparatus before they are extruded through the spinning or extrusion orifices. This is particularly objectionable when it is required that the components which show a tendency to inter-diffuse be kept strictly separated.

Such inter-diffusion of the two components may even

2

be so rapid that in the final filaments there can no longer be distinguished any layered structure.

For various applications of the yarns obtained by such spinning techniques, especially as far as textile is concerned, it is necessary that the individual filaments have accurately constant and identical compositions. It has been found that with the known apparatus, this is often not possible. This is again due to the fact that the spinning mass, between leaving the mixing device and entering the spinning orifices, is exposed to many kinds of adverse phenomena.

Advantageously, the drawbacks enumerated above are not encountered when the apparatus and process of this invention are employed. Furthermore, the apparatus and process of the invention also provide many additional advantages heretofore not obtained.

Thus, this invention contemplates an apparatus for producing multifilament yarns comprised of filaments having a layered, multicomponent structure which comprises spinneret means having extrusion orifices for forming a plurality of filaments, mixing means immediately upstream of and in contact with said spinneret means, and feed means for introducing spinning masses of each component separately into said mixing means, said mixing means providing a system of channels which form a plurality of parallel mixers, each mixer terminating into one of said extrusion orifices and having stationary elements arranged to form the spinning masses introduced by said feed means into a layered stream of said components and thereafter to repeatedly divide and increase the component layers therein whereby each of said extrusion orifices form one of the multicomponent filaments of the multifilament yarn.

It will be appreciated that the apparatus of the invention can be used not only for mixing two entirely different spinning masses but also for homogenizing a single spinning mass prior to the extrusion of a plurality of filaments.

When the apparatus is used to manufacture filaments having a layered structure from two different spinning masses, it is preferred to use a construction in which the feeding means for introducing the spinning masses includes a distribution plate that is placed upstream of the mixing means. The distribution plate has two branched channel systems which are each connected to a central feed inlet for one of the spinning masses. The final branches of each of the two channel systems communicate in pairs with each of the parallel mixers in the mixing means.

With the aid of the distribution plate all the mixers inside the mixing means are fed in an identical manner and the spinning masses fed to these mixers are identically intermixed immediately before entering each extrusion orifice. As a result, the filaments that are spun from the spinneret have all along their length absolutely identical and constant compositions. Moreover, since the two spinning masses are intermixed practically immediately before they are extruded, the influence of interdiffusion of the two spinning masses is considerably reduced. In fact, it is possible now to make layered filaments from spinning masses where heretofore, it has been practically impossible to obtain such filaments.

It should be noted that apart from the afore-discussed phenomenon of diffusion as a potential source of trouble which prevents the formation of filaments having a layered structure, there are other phenomena which may have a disturbing influence. For example, the influence of the surface tension of the two components, a chemical interaction of the two components, and the like. Since in the apparatus according to this invention the various spinning masses are in contact with each other only for

a very short period before the filaments are solidified, the influence of all these disturbing factors is strongly reduced.

The mixing means used by the apparatus may be constructed in various ways. Examples of mixing apparatus of the type used in the invention are generally described for instance in the Netherlands patent specifications 109,-918 and 111,082.

The mixers in the mixing means of the invention, however, should have minimum dimensions to allow provision in the spinneret for a maximum number of spinning or extrusion orifices. For practical reasons many constructions are therefore unsuitable. It has been found that one embodiment which is very suitable for mass production may be obtained if according to the invention the mixing means is built up of a plurality of stacked mixing disks through which there run unbranched channels and in which pairs of adjacent channels in one disk terminate in adjacent channels of the disk placed below.

In accordance with this invention the mixing disks preferably are constructed so that they have a large but even number of substantially parallel unbranched channels which (1) adjoin in pairs all along their length; (2) make a quarter turn about each other; and (3) in the direction in which they are turned, first narrow and then widen. Such a mixing disk having channels of very small dimensions can, by precision casting, be constructed from all kinds of materials. It has been found that the usual distances between the spinneret orifices need hardly be increased when such mixing disks are employed.

This invention is also directed to a process for producing the multifilament yarns which comprises dividing the spinning mass of each of at least two components into a plurality of separate streams, uniting the separate streams of one component with those of another to form a plurality of layered streams, dividing and reuniting each of the layered streams separately to produce multi-layered streams having alternate layers of each component therein, passing each multi-layered stream through one of the extrusion orifices in a spinneret to form a plurality of multicomponent layered filaments, solidifying the filaments and thereafter combining said filaments into a yarn.

Finally, the invention also is concerned with the multifilament yarns made by the present process. It has been found that these yarns show a very great uniformity and lend themselves very well for all kinds of novel effects. These yarns may be made up of components with which it previously has been impossible to form a layered structure within a single filament. This is particularly true in the case of components which rapidly inter-diffuse when used in a spinning mass and applies to many of the spinning masses that are spun to form filaments by the melt-spinning process or the dry-spinning process.

The apparatus according to this invention provides various additional advantages over the known apparatus. For instance, the mixing means used is very simple to disassemble, clean, and reassemble. Also, the number of layers in the filaments produced may satisfactorily be fixed by the choice of the number of mixing disks. The number of layers may be made from an even-numbered series, i.e., 2, 4, 8, 16, 32, etc. Changing the number of layers hardly gives any difficulties as far as construction of the apparatus is concerned. Since the channel openings are very much wider than the spinning orifices, the spinning mass in the mixing disks is hardly subjected to any flow resistance. It is therefore simple to convert existing spinning equipment into the new apparatus without it being necessary for the equipment to be completely redimensioned.

It has been found that in most spinning processes it is necessary for the spinning mass to be filtered prior to extrusion in order to guarantee a smooth spinning process. In the apparatus according to the invention the various spinning components are intermixed very shortly before

they reach the spinning orifices. Thus, it is possible for the spinning masses to be filtered before they flow through the mixing disks. The flow pattern is consequently not disturbed then by the inevitably required filtration. It has even been found that in the present apparatus the filtration need be less thorough. This is to be attributed to the fact that before the spinning masses pass through the spinning orifices they are very thoroughly worked or kneaded.

10 The invention will be further described with reference to the accompanying drawings in which:

FIG. 1 is a diagrammatic view of a spinneret assembly of the invention with a fragment broken away showing a longitudinal section;

15 FIG. 2 shows a plan view of the arrangement of parallel channels on a mixing disk used by the apparatus of the invention;

FIG. 3 is an enlarged sectional view taken from the section shown in FIG. 1; and

20 FIG. 4 is a plan view showing an enlargement of the inflow openings on a mixing disk.

25 In FIG. 1, the reference numeral 1 designates a housing of a spinneret assembly. Viewed from top to bottom, i.e., the direction of flow of the spinning mass through the assembly, the housing contains, positioned one on top of another, a distribution plate 2, a mixing disk 3, another mixing disk 4, and a spinneret or orifice plate 5. These parts are shown in longitudinal section within the broken away portion of the figure. The spinneret 5 is of a conventional type and provided with spinning orifices 9 which have a relatively wide initial bore that converges into a narrow outflow opening.

30 The distribution plate is connected to two inlet conduits 6 and 7 for the different spinning masses. Each of the feed conduits ends in a separate system of channels provided in the distribution plate. The final branches of these channel systems end or terminate opposite the pairs of channels 8 which run through the mixing disk 3. The channels 8 lead to similar channels 8' running through the lower mixing disk 4. The last-mentioned channels lead to the spinning or extrusion orifices 9 of the spinneret.

35 FIG. 2 is a plan view of a mixing disk which shows the relative positions of the pairs of channels. These channels are arranged so that the inflow and outflow openings or passages of each pair lie within cylindrical planes having a square cross-section. As shown in FIG. 1, when placed in the housing of the spinneret assembly, each pair of channels in mixing disk 3 is positioned directly over a pair of channels 8' running through the mixing disk 4. As a result, the spinning mass which flows into a pair of channels 8 of the mixing disk 3 passes, in its entirety, and exclusive of the other spinning masses, into only one spinning orifice 9 of the spinneret 5.

40 From FIG. 4 it is apparent that the two channels 18 and 19, which together form a pair of channels, have rectangular adjacent inflow openings, and that parallel to the partition 22 which separates them, these channels narrow in opposite directions to openings having square cross-sections. From these square openings the channels 18 and 19 then widen in opposite transverse directions until they have reached their original rectangular shape. (It will be understood that in each channel the outflow passage is arranged transversely to the inflow passage.)

45 In FIG. 3 it can be seen that the channels 18 and 19 through the mixing disk 3 are positioned over and terminate adjacent to identical channels through the mixing disk 4. But it should be also noted that the lower partitions 22' between the channels 18 and 19 are at right angles to the partitions 24 between the inflow passages of channels 20 and 21 in disk 4. With this arrangement the layered spinning mass issuing from each of the channels 18 and 19 is uniformly distributed over each of the channels 20 and 21.

50 It will be understood the mixing action of the series of channel pairs 18, 19, and 20, 21 is identical with that of

the channels provided in the mixers described in the Netherlands patent specifications 109,918 and 111,082.

From inspection of FIGS. 1 and 3, it will be understood that a spinning mass is fed through the central feed inlet 7 (omitted from FIG. 3) to a system of channels 10 in the distribution plate 2. From each of the channels of this system the spinning mass is fed through openings or passages 11 to chambers 13. Likewise, a different spinning mass is fed from the feed inlet 6 (omitted from FIG. 3) to a second system of channels (not shown) and then through openings or passages 12 to chambers 14. The chambers 13 and 14 are separated by partitions 15, 16, and 17.

Chambers 13 and 14 form outflow openings having a square cross-section each of which (as shown in FIG. 3) covers half the surface area of the inflow openings of two adjacent pairs of channels 18 and 19. As a result, a spinning mass is fed from the feed inlet 6 into one half of each of the channels 18 and 19 and another spinning mass is fed from the feed inlet 7 into the other half of each of these channels.

After these spinning masses have passed serially through the two mixing disks 3 and 4, the resulting stream of spinning mass which flows to each of the spinning orifices 9 is composed of eight component layers. Each filament spun from one of the spinning orifices 9 is therefore also composed of eight component layers.

It will be clear that depending on the choice of the number of mixing disks used, the number of component layers in each filament may be varied by the series 2, 4, 8, 16, etc.

It has been found that the system of channels provided by the mixing disks permits the spinning orifices in the spinneret 5 to be closely spaced. Furthermore, the channels extending through the mixing disks 3 and 4 may be so small that the pairs of channels 8 (and the channels 8') are spaced apart at a pitch distance of 6 mm. In practice, the pitch distance of the spinning orifices in a spinneret is seldom less than 6 mm.

It will be appreciated that in accordance with this invention, many combinations of components may be used to prepare the desired fibrillary products, i.e., the multifilament yarns. The most appropriate combination will depend on the intended application. Exemplary of some possible combinations of the components are nylon and polypropylene, nylon and polyester, polypropylene and polyethylene, nylon and polystyrene, polyester and polystyrene, polyacrylonitrile and polyvinyl alcohol, nylon and polyvinyl alcohol, and the like.

It will be understood that it is preferred that the components be selected so that they are substantially immiscible with each other.

It will also be appreciated that although the invention is principally concerned with production of multifilament yarns, the multicomponent layered filaments produced thereby are also highly useful products.

While the novel features of the invention have been shown and described and are pointed out in the appended claim, it is to be understood that various omissions, modifications and substitutions in the features shown and de-

scribed may be made by those skilled in the art without departing from the spirit and scope of the invention.

What is claimed is:

1. In an apparatus for producing layered, multi-component filaments, the improvement which comprises, in combination, (1) spinneret means having extrusion orifices for forming a plurality of filaments, (2) mixing means immediately upstream of and in direct contact with said spinneret means, and (3) feed means for introducing spinning masses of each component separately through filtration means into said mixing means, said mixing means comprising a plurality of mixing disks stacked one upon the other, said mixing disks having an even number of unbranched channels, said channels being substantially parallel to each other and being so arranged that they adjoin in pairs all along their lengths, each of said channels making one quarter turn about itself and in the direction in which the channel is turned, said channels first narrowing and then widening, each of said mixers comprising a pair of adjacent channels in one disk which end in the adjacent channels of another mixing disk, said feed means including a distribution plate positioned upstream of and in communication with said mixing means, said distribution plate having two branched channelled systems which are each connected to a feed inlet for one of the spinning masses, the final branches of each of the two channel systems communicating in pairs with each of the parallel mixers, each mixer terminating into one of said extrusion orifices.
